UNITED STATES PATENT OFFICE.

RUDOLF COMMICHAU, OF MAGDEBURG-SUDENBURG, GERMANY.

SPIRAL CONVEYER.

SPECIFICATION forming part of Letters Patent No. 626,409, dated June 6, 1899.

Application filed January 19, 1899. Serial No. 702,693. (No model.)

To all whom it may concern:

Be it known that I, RUDOLF COMMICHAU, a subject of the King of Prussia, Emperor of Germany, residing in Magdeburg-Sudenburg, 5 in the Kingdom of Prussia, Germany, have invented certain new and useful Improvements in Spiral Conveyers, (for which a patent has been applied for in Germany and which application is dated May 4, 1898,) of which the 10 following is a specification.

My invention relates to an improvement in spiral conveyers. According to the processes of manufacture conveyers are made of separate rings, which are punched out, slotted at 15 the side, bent, and riveted together in the transverse direction, and it is not possible to so fashion the outer edge (which owing to the greater peripheral speed wears away much quicker than the inside) that the wear takes 20 place equally over the whole surface.

The object of my invention is to remedy this disadvantage in making the conveyers by rolling them out of straight strips of metal. For this purpose I preferably use the rolling- 25 machines described broadly, for instance, in German Patents Nos. 55,692, 64,571, 21,547, and 87,681, and the United States Patent No. 499,713, of June 20, 1893, United States Patent No. 368,569, of August 23, 1887, or 30 United States Patent No. 601,429, of March 29, 1898, with this difference, however, that in order to obtain a thickened edge the material must have a wedge-like-shaped section and that the rollers must be capable of being ad- 35 justed in such a position that the material re- ceives the proper curvature and yet retains certain taper toward the edge. The rolls them- selves may be cylindrical or conical and ar- ranged in two or more juxtaposed or super- 40 imposed groups. Apart from the fact that the duration of conveyers constructed in this way is considerably prolonged, as in working they can be used for the conveyance of ma- terials which attack the metal of the con- 45 veyer, as is the case in mills where gypsum, slag, salt, &c., are treated, they also possess the great advantage for other kinds of work

that both the rivets and the transverse joint, which were unavoidable in one mode of construction hitherto followed, are done away with, thus permitting the conveyers to be used for the conveyance of materials, such as crystallized sugar and other salts, &c., which are very liable to be easily triturated or to be otherwise damaged by friction. 50

The mode of construction described in the foregoing renders it possible to make the conveyers of several spiral strips riveted together along the direction in which the conveying motion takes place—that is to say, in such a 60 manner that a strip of thicker material with countersunk rivets is fixed to the one attached to the shaft, whereby the strip can be renewed when it is worn out and the conveyer further utilized without incurring great expense. 65

Figure 1 is a perspective view of a strip of material having a wedge-like section. Fig. 2 is a view showing a machine for bending the material into the spiral conveyer, and Fig. 3 is a side view of a complete conveyer. 70

In said figures, A represents the strip of metal, and B B' are two conical-ended rolls, between the ends of which the material passes and by means of which it is formed into the spiral conveyer. This spiral-conveyer strip 75 is then suitably mounted on a proper supporting shaft or rod C, as indicated in Fig. 3, and the spiral conveyer thus formed has the thickened edge a.

Having described my invention, what I 80 claim is—

As a new article of manufacture, a spiral conveyer comprising a supporting-shaft and a metallic spiral screw-strip mounted thereon, the strip being tapering in cross-section with 85 its thickest portion at the periphery of the strip, substantially as described.

In witness whereof I have hereunto signed my name in the presence of two subscribing witnesses.

RUDOLF COMMICHAU.
